UNITED STATES PATENT OFFICE

BARNETT B. ROCHESTIE, OF TRENTON, NEW JERSEY

DESIGN FOR A WEIGHING MACHINE CASING

Application filed June 7, 1932. Serial No. 44,010. Term of patent 3½ years.

To all whom it may concern:

Be it known that I, BARNETT B. ROCHESTIE, a citizen of the United States, residing at Trenton, in the county of Mercer and State of New Jersey, have invented a new, original, and ornamental Design for a Weighing Machine Casing, of which the following is a specification, reference being had to the accompanying drawing, forming part thereof.

Fig. 1 shows a perspective view of the weighing machine casing.

Fig. 2 shows a side elevation thereof.

I claim:

The ornamental design for a weighing machine casing as shown.

In testimony whereof, he affixes his signature.

BARNETT B. ROCHESTIE.
